UNITED STATES PATENT OFFICE.

HENRY J. GEER, OF PROVIDENCE, RHODE ISLAND.

COMBINED TOY WRIST-WATCH AND WHISTLE.

1,306,662.

Specification of Letters Patent. Patented June 10, 1919.

Application filed February 20, 1919. Serial No. 278,144.

To all whom it may concern:

Be it known that I, HENRY J. GEER, a citizen of the United States, residing at Providence, in the county of Providence and 5 State of Rhode Island, have invented certain new and useful Improvements in Combined Toy Wrist-Watches and Whistles; and I do declare the following to be a full, 10 clear, and exact description of the invention, such as will enable others skilled in the art to which it appertains to make and use the same.

This invention relates to toys, and it relates more specifically to a combined toy 15 wrist-watch and whistle.

One object of this invention is to provide a device of this character in which a body simulating a watch and comprising a whistle is spaced from the strap or attaching element that secures it to the wrist of a person, thereby providing an air-passage or space 20 through which air may pass out from the whistle.

A further object is to provide a device of 25 this character consisting of only a few very simple parts so that the cost of manufacture is minimized.

Other objects and advantages may become 30 apparent to persons who read the following details of description in connection with the accompanying drawings, in which:—

Figure 1 is a side elevation of my improved toy;

Fig. 2 is a front view of the toy;

Fig. 3 is an enlarged central sectional view, the section being taken along the line 3—3 of Fig. 2.

Referring to these drawings in detail, in 40 which similar reference characters correspond with similar parts throughout the several views, the device consists of five primarily separate parts 5, 6, 7, 8 and 9, respectively.

The part 5 comprises a cylindrical portion 45 10, an annular flange or inturned portion 11 and two apertured ears 12. Through the apertures 13 of these ears the strap or flexible attaching element 9 extends, and its intermediate portion spans or bridges the 50 space between the apertures 13.

The members 7 and 8 are preferably concavo-convex, and the concavo sides are turned inward toward one another, while 55 their edges meet at 14. In other words, these two members 7 and 8 are fitted together to form a hollow body of thin metal or other

appropriate material. The member 7 is provided with an inlet opening 15, and the member 8 is provided with an outlet opening 16. The member 6 is provided with an 60 inlet opening 17, and the inlet openings 15 and 17 register with one another and may properly be considered as constituting a single inlet opening. The member 7 is formed with a dial 18 to simulate that of a 65 watch, and this dial is visible through the member 6 which is formed of any appropriate transparent material. The periphery of the member 8 may be secured within the cylindrical wall 10 by any appropriate 70 means, and the relative circumferences of the members 5 and 8 may be such that the latter fits tight enough in the member 5 to be held by the frictional engagement of the outer periphery of the member 8 and the 75 inner periphery of the member 5.

The ears 12 are preferably made integral with the cylindrical part 10 of the member 5, and these ears extend laterally of the surface having the outlet aperture 16 therein. 80 The lateral extent of the ears 12 beyond the last mentioned surface is sufficient to provide an air-passage between the element 9 and the outlet opening 6 when the adjacent portion of the attaching element is straight, as 85 shown in Figs. 1 and 3, or even when it is somewhat bowed or bent toward the opening 16. In other words, if a straight line is drawn between the inner edges of the apertures 13, the distance between such line and 90 the opening 16 will be more than sufficient to provide a passage for the air which is necessary to make a whistling sound when a person blows into the inlet opening 17. Therefore, it will be seen that when the strap 9 95 is placed around the wrist of a person, even the lateral curvature of the wrist is not ordinarily sufficient to close the space between the opening 6 and the adjacent part of the strap 9. Moreover, the ears 12 are sufficiently 100 pliable to enable them to be bent so as to bring their outer ends nearer one another, so that when the device is to be applied to an unusually small and cylindrical wrist, the distance between the opening 16 105 and strap 9 is increased, while the geometrical chord (represented by a line connecting the apertures 13, in connection with the curve of the strap 9) is shortened.

Although I have described this embodiment of my invention very specifically, it is not intended to limit this invention to

these exact details of description and arrangement of parts, but I am entitled to make changes within the scope of the inventive idea disclosed in the foregoing description and following claim.

What I claim as my invention is:—

In a device of the character described, a hollow body having an inlet opening and an outlet opening to provide a whistle, apertured supporting ears united with said body and extending laterally of the body's side having said outlet opening therein, and an attaching element having a portion extending through the apertures of said ears and

spanning the space between these apertures, 15 the distance from the outlet opening to a straight line through said apertures being sufficient to provide an air passage when said portion of the attaching element is straight or somewhat bent inward toward 20 said outlet opening.

In testimony whereof I have hereunto set my hand in the presence of two subscribing witnesses.

HENRY J. GEER.

Witnesses:

JOSEPH J. CUNNINGHAM,
PATRICK J. NANGLE.
